TIMING DIAGRAM

The diagram illustrates the timing of various mechanisms in degrees, spanning from 0° to 360°. The mechanisms include:

- Painting Mechanism Angle:** 0° to 360°.
- Operation of Lamp Finishing Machine Turret:** 120° to 360°. It includes "INDEXING ENDS (85°)" and "TURRET IS STOPPED AND BASE HOLDER IS FIXED AT PAINTING STATION." at 240°.
- Right Hand Slide Rod (Printing Stamp):** 20° to 120°. It includes "100° FORWARD, 20° BY SPRING ACTION" and "100° BACKWARD, 20° BY SPRING ACTION" at 100°.
- Left Hand Slide Rod Movement:** 70° to 170°. It includes "100° FORWARD, 10° BY SPRING ACTION" and "100° BACKWARD, 10° BY SPRING ACTION" at 120°.
- Jaw Movement and Opening:** 10° to 100°. It includes "JAWS REMAIN OPEN, FINGERS CLOSE, JAWS OPEN, JAWS CLOSE AND STAMP PICKS UP INK." at 100°.
- Stamp Inking Controls and Interlock:** 20° to 100°. It includes "LARGE ROLLER MAY RELEASE INTERLOCK" and "SMALL ROLLER RELEASES INTERLOCK" at 100°.
- Patent is Indexed:** 100° to 360°. It includes "INDEXING BEGINS (325°)" and "100° BACKWARD, 10° RETREAT OF 3° BY POSITIVE CAM ACTION, 100° BACKWARD, 10° RETREAT OF 3° BY POSITIVE CAM ACTION." at 330°.

LAMP BASE PRINTING MECHANISM

Leslie P. Tyler, Cleveland Heights, Ohio, assignor
to General Electric Company, a corporation of
New York

Application December 16, 1950, Serial No. 201,087

10 Claims. (Cl. 101—38)

1

This invention relates generally to the printing of identifying characters on cylindrical objects such as the bases of incandescent lamps. More particularly, it relates to a mechanism for automatically printing identifying characters on the cylindrical bases of miniature electric lamps and which is adapted to operate in conjunction with rotary turret lamp finishing machines.

The lamp making machines used in the industry at the present time are generally of the indexing type wherein manufacturing operations are performed upon the lamps at spaced work stations. The lamps are advanced or indexed from one work station to the next by means of suitable conveyor systems which operate in a series of intermittent or discontinuous steps. For instance, the lamps may be held by the spindles of suitable holders mounted on the periphery of a rotary turret; the manufacturing operation may be performed by mechanical operators disposed around the turret at various stations and adapted to move radially inwards upon the lamps when they are indexed in place. The wide-spread use of machines of this type has made it practically essential that a printing or lamp marking mechanism be capable of operating in conjunction with them in order to be economically feasible.

The marking of electric lamps is generally required in order to permit their identification as to wattage and rating and usually as to the maker. In the case of the larger lamps, for instance, the household type of lamp adapted to operate on the commercial 110-volt circuits, such markings are relatively easily applied to the curved exterior surface of either the lamp or the base. The marking may be done by means of printing members or templates having a curvature conforming to that of the envelope of the lamp or other portion whereon it is desired to impress the printing. Another device which has been employed is a crescent-shaped printing member which is adapted to swing upon the base of a lamp during the period of time when the lamp is indexed at a predetermined printing station. Although such a method of printing is perfectly satisfactory when the curvature of the surface is moderate or, in other words, when the printing covers only a fraction of the periphery of a cylindrical base, it is not feasible as a rule when the printing must cover a major portion of the periphery of the base. Particularly in the case of miniature incandescent lamps wherein the printed characters must cover substantially the whole periphery of the base in order to be

2

eligible, such curved printing members are generally not feasible.

In the copending application of Harry C. Atkins et al., Serial No. 195,448, filed November 13, 1950, entitled "Base Printing Apparatus" and assigned to the same assignee as the present invention, there is disclosed and claimed an apparatus for printing identifying characters on miniature incandescent lamps. The apparatus in that application comprises a pair of slideable arms which are adapted to swivel together to grasp a lamp by its base, and to slide one with respect to the other in order to roll the base. One of the arms carries a printing member which prints the characters on the base during the rolling operation.

The present invention relates to an improved base printing machine of the same generic type as that described in the Atkins et al. application above, and which is particularly suitable for operation in conjunction with a high speed miniature lamp finishing machine.

Accordingly, the principal object of my invention is to provide a new and improved printing mechanism for operating in conjunction with a lamp finishing machine of the rotary turret indexing type for applying identifying characters of substantial size around the periphery of miniature electric lamp bases.

In accordance with the invention, the characters are printed on the base of the lamp by rolling it against a flat stamp suitably inked for the purpose. The stamp is mounted next to one of a pair of serrated gripping plates which are held on radial fingers fastened to a pair of slide rods. The gripping of the lamp is achieved by means of a slight inward rotation of the rods along their longitudinal axes, one with respect to the other, and the rolling of the lamp between the serrated gripping plates is achieved by causing one of the rods to slide backwards as the other slides forward, both at equal rates with respect to the spindle of the lamp finishing machine which holds the lamp.

For further objects and advantages and for a better understanding of the invention, attention is now directed to the following description and accompanying drawings. The features of the invention believed to be novel will be more particularly pointed out in the appended claims.

In the drawings:

Figs. 1a, b, and c are simplified fragmentary views of the main elements of the printing mechanism, showing in pictorial form the sequence of operations in printing a lamp base.

Fig. 2 is a plan view, partly in section, of a base printing mechanism embodying the invention and shown in conjunction with a fragment of a lamp finishing machine.

Fig. 3 is a side elevation view of the printing mechanism shown in conjunction with a single lamp base holder.

Fig. 4 is an enlarged side elevation view of a miniature incandescent lamp showing the type of marking or characters which it is desired to imprint on the base of the lamp.

Fig. 5 is a sectional elevation of a portion of the base printing mechanism seen along the section line V—V in Fig. 2.

Fig. 6 is a plan sectional view showing a fragment of the printing machine including a pair of control rollers forming part of an interlock mechanism.

Fig. 7 is a plan sectional view through the section line VII—VII in Fig. 5, showing the serrated gripping jaws and the printing stamp of the machine positioned for marking a lamp base.

Fig. 8 is a timing diagram showing the sequences of operations in the mechanism during a printing cycle.

Referring to Fig. 4, there is shown a miniature incandescent electric lamp 1 of a type which is produced in large quantities by the lamp making industry, generally for use in flashlights. The major component parts of the lamp are the base 2 which, in this case, is of the miniature screw type, and the glass bulb 3 containing the filament. In general, the manufacturing operation of the lamp finishing machine to which reference is made in the present application comprises joining the bulb to the base, heating the base in order to set the cement contained therein, and soldering the lead-in wires, one to the end contact 4, and the other to the base shell. The purpose of the printing mechanism of the present invention is to print identifying characters such as the markings "0014 . . . USA" on the base of the lamp, as shown at 5 in the drawing. Although the identifying characters shown in the drawing cover only a fraction of the periphery of the base, in practice the name or trade-mark of the manufacturer of the lamp would also be printed so that the characters would cover substantially the whole periphery of the base.

Referring to Fig. 1, the essential functional elements of the printing mechanism for operating on the base 2 of lamp 1 comprise the printing stamp 6, the cooperating serrated gripping plates or jaws 7 and 8, and the slide rods 10 and 11 to which the jaws are attached by the radial spring fingers 12 and 13. The different views *a*, *b*, and *c* illustrate the sequence of operation of the mechanism in printing the identifying characters on the base 2. It will be understood that the lamp is held in the position shown by means of a suitable holder but is free to spin on its vertical axis.

In Fig. 1*a*, the slide rods are shown in their retracted position and rotated about their longitudinal axes in such fashion that the jaws are spread apart. From the position shown in Fig. 1*a*, the slide rods advance towards the lamp to assume the position shown in Fig. 1*b*. The rods then rotate about their longitudinal axes in opposite directions one with respect to the other so as to force the gripping jaws inwardly together in order to grasp the lamp. In Fig. 1*c*, the lamp is caused to rotate or spin in its holder by reason of the equal rectilinear movement of the slide rods in opposite directions. Thus slide rod 11

continues to move forward whereas slide rod 10 moves backward an equal amount and at the same rate. During the spinning operation, the stamp 6 carried under the gripping jaw 7 bears against the base of the lamp so that the characters are printed on it. The next operation of the slide rods evidently must be to rotate about their longitudinal axes so as to open the gripping jaws and release the lamp, whereupon both slide rods will be retracted to the position shown in Fig. 1*a*.

The base printing mechanism, which will now be described in detail by reference to the remaining figures of the drawings, is designated to effect the above-described sequence of operations on a lamp held in a holder of a lamp finishing machine of conventional design. Evidently the sequence of printing operations must be correlated to the indexing cycle of the finishing machine in order for the mechanism to operate successfully. It is necessary to provide for inking the printing stamp during some portion of the cycle of the mechanism. Since it is possible for a lamp holder which does not contain a lamp to be indexed to the printing station, suitable provision must also be made to safeguard the operation of the printing mechanism in such a contingency. The safeguards are provided by means of an interlock mechanism which prevents the inking of the stamp when no lamp is present in the holder.

In order to simplify the description of the mechanism which will now follow, and to facilitate an understanding of its operation, the mechanism will be considered under the following headings:

- 35 1. Slide Rod Mechanism
2. Inking Mechanism
3. Interlock Controls
4. Timing Diagram

Slide rod mechanism

Referring to Fig. 2, the lamps are held in holders 16 which are fastened radially on the periphery of a wheel or turret 17 rotatably supported at its center on a shaft 18. The finishing machine is provided with a suitable power drive for intermittently rotating the turret 17 in a counter-clockwise direction, as indicated by the curved arrow 19, through a continuous series of small angular increments. These angular increments are such that the base holders advance through one position for each indexing operation of the turret. Thus at the next indexing operation, lamp holder 16' will move to the position occupied by lamp holder 16' in the drawing, whereas lamp holder 16' will move to the position presently occupied by lamp holder 16.

The details of the lamp holder 16 may be seen in Fig. 3. It comprises a bracket 21 which is fastened to the turret 17 and supports at its upper end a lamp base receiving plate 22 shaped to conform to the outer end of the base 2 of the lamp 1. The lamp is held in the plate 22 by means of a spindle 23 provided with a suitable fixture 24 adapted to bear against the bulb 3 of the lamp. A helical spring 25 pushes the spindle 23 and the fixture 24 up against the lamp, thereby to hold it securely in place against plate 22. The lamp may be released by pressing down on the bracket 26 in order to compress the spring 25 and drop the spindle 23.

Referring to Fig. 2, the slide rods 10 and 11 along with the associated parts constituting the printing mechanism are located, with respect to the turret 17, to operate upon the lamp presently held at the printing station, that is, the

lamp 4 held in holder 16. The slide rod 10 which supports the printing stamp will henceforth be referred to as the right-hand slide rod, and the other as the left-hand slide rod.

The reciprocating movement of the slide rods in their guide bearings is achieved by means of spring loaded cam actuated levers. In the case of slide rod 10, the component elements may readily be seen in Fig. 3. They comprise a connecting lever 27 which is hinged at 28 and carries, at its lower end a roller 29 riding in a vertical slot in the rod 10, and at an intermediate point, a roller 31 which rides on a cam disc 32 fastened to a shaft 33. Shaft 33 is driven by means of a roller chain and sprocket, shown generally at 34, which links it by means of a worm and pinion shown generally at 35, to the cam shaft 36 of the lamp finishing machine. It will be understood that the cam shaft 36 is driven at a constant angular velocity by the power drive of the lamp finishing machine, and not in a series of intermittent steps.

The slide rod 10 moves in an annular guide bearing block 37 which is fastened to a vertical frame plate 38 supported by suitable brackets at 41 and 42. The retreat or backward movement of the slide rod 10 away from the lamp holder is brought about by the positive action of the cam disc 32 against the roller 31 on the connecting lever 27. The advance or forward movement of the slide rod towards the lamp holder is caused by the action of the coil spring 43 when the cam disc 32 allows it. The knurled thumb screw 44 permits a slight movement of the pivot 28 to the left or right in order to allow a fine adjustment of the limits of movement of the slide rod 10.

The slide rod 11 has a mechanical linkage similar to that of the slide rod 10, comprising a cam disc 45 which may be seen in dotted outline in Fig. 3, and a connecting lever 46 which may be seen in cross section in Fig. 2. The cam disc 45 is also fixed to the shaft 33 and drives the slide rod 11 through a linkage with lever 46 and associated elements similar to those that have been described with reference to slide rod 10.

As previously mentioned with reference to Figs. 1a, b, and c, it is necessary to periodically rotate the slide rods 10 and 11 about their longitudinal axes with respect to their guide bearings in order to bring the serrated gripping jaws 7 and 8 together. This is achieved by a slide and roller mechanism in the following manner: The slide rods 10 and 11 are free to rotate in their guide bearings 37 except inasmuch as they are restrained by the transverse pins 47 and 48 supporting rollers 49 and 50, respectively. These rollers, as may be seen in Fig. 3, ride in horizontal slots 51 and 52 in a slide or cross-head 53 which is fastened to a vertical spindle 54. This spindle carries at its upper end a roller 55 which bears against the intermediate cam disc 56, fastened like the others to the transverse shaft 33 and driven by the roller chain and sprocket linkage 34. The spindle 54 is normally urged upward by the coil spring 57 which causes the roller 55 to bear against the cam disc 56. The slide rods rotate in such fashion that the gripping jaws are forced apart by a downward movement of the cross-head. Since the gripping jaws are mounted at the ends of the relatively long spring fingers 12 and 13, a very slight movement of the cross-head is amplified to produce a considerable movement of the gripping jaws. It will be observed that the jaws are forced

apart by the positive action of the disc cam 56, whereas they are brought together by the reverse action of the spring 51. This prevents damage to the jaws in case they should encounter an obstruction in attempting to close upon a lamp.

Inking mechanism

It is necessary to provide some means for inking the stamp 6 in the intervals between printing operations on a lamp. In accordance with the invention, this is achieved by causing the jaws to close together at or near to the limit of rearward travel of the slide rods. Referring to Fig. 3, it will be observed that the printing stamp 6 is located beneath the right-hand gripping jaw 7 and is fastened to the slide rod 10 by means of a spring blade 58. The mounting screws 59 at the lower end of the spring blade 58, in conjunction with the horizontal slot in the printing stamp 6, permit adjustment of the position of the stamp. When the jaws close together in the position shown, the printing stamp contacts the disc platen 61 and picks up ink for the next printing operation. Referring to Fig. 5, the position of the printing stamp in picking up ink from the disc platen 61 is readily seen. The platen 61 is mounted on a short spindle 62 which carries at its opposite end a sprocket wheel 63. The ink is supplied to the platen by a vertical roller 64 which receives it from a horizontal roller 65, which in turn receives its ink from a V-shaped inking reservoir 66 of conventional design.

The vertical roller 64 is adapted to rotate on a shaft which is supported by the bracket 67 extending downwardly from the slide rod 10. During a reciprocation of the slide rod 10, the vertical roller 64 rolls over the platen 61 and spreads the ink, which it has picked up from the horizontal roller 65, over the surface of the platen. The rearward movement of the slide rod 10 causes the roller 68 affixed to the bracket 67 to contact the bell crank 69. By means of a suitable spring and pawl arrangement which may be seen in part at 71, the rocking of the bell crank 69 indexes the horizontal roller 65 through a predetermined angle so that it continuously picks up ink from the reservoir 66. The shaft on which the horizontal roller 65 and the bell crank 69 are mounted, also carries at its remote end a sprocket which is linked by a roller chain to the sprocket 63 shown in Fig. 5. As a result, the indexing of the horizontal roller 65 also causes the disc platen 61 to be indexed through a small angle, thereby causing it to revolve intermittently. The revolving of the disc platen 61 along with the to and fro movement of the vertical roller 64 helps in spreading the ink evenly as a thin film on the disc platen.

The quantity of ink picked up by the vertical roller 64 can be varied by adjusting the pressure under which it contacts the horizontal roller 65. This adjustment is effected by turning the knurled thumb screw 44 to shift the pivot point 28. The vertical roller 64 is made of some flexible material such as rubber and picks up a greater or lesser quantity of ink, depending upon the extent to which it is deformed against the horizontal roller 65.

Interlock controls

The purpose of the interlock controls is to prevent the accumulation of ink on the printing stamp which would occur when empty base holders are indexed into the printing station. It

will be understood that it quite often happens that the personnel attending the lamp finishing machine may fail to fill all the lamp holders in any one revolution. Accordingly if the printing stamp were allowed to pick up the same amount of ink irrespectively of whether or not lamp bases are being printed, the ink would accumulate on the stamp. Then, when eventually a holder containing a lamp did become indexed at the printing station, the characters printed on that particular lamp would be blurred due to the running over of the excess of ink. The mechanism counters such a possibility by means of a mechanical interlock which prevents the printing stamp from picking up ink whenever an empty lamp holder is indexed into the printing station.

The principal elements of the interlock mechanism may be seen in Fig. 6 which is a plan view of that portion of the machine next to the lamp holder on a level slightly vertically above the turret 17, and corresponding approximately to the top surface of the stud 26 projecting horizontally from the spindle of the lamp holder. The principal elements of the interlock mechanism are the lever 73 which is pivoted at 74 with respect to the vertical frame 38 of the printing mechanism, and which is normally forced in a counterclockwise direction by the coil spring 75. The lever 73 carries at its end nearest the lamp spindle a large roller 76 and a smaller roller 77. At its end remote from the lamp holder, the lever 73 carries a vertical screw 78 whose head is adapted to engage a transverse pin 79 on the vertical spindle 54 which supports the cross-head 53. It will be recalled that the up and down movement of the cross-head 53 controls the axial rotation of the slide rods whereby the gripping jaws are brought together or forced apart. Since the upward movement of the cross-head which causes the jaws to close is brought about by the action of the coil spring 57, it is possible to prevent the jaws from closing by restraining the upward movement of the rod 54. The restraining of the rod 54 is achieved by the head of the screw 78 which may engage the transverse pin 79 on the spindle.

The operation of the interlock is correlated to the presence or absence of a lamp within a holder by the fact that the presence of a lamp results in the spindle 23 of the holder being depressed slightly lower than when a lamp is absent. The roller 76 is so positioned that if a lamp is present within the holder, the stud 81 on the spindle of the lamp holder contacts it and causes the lever 73 to pivot, whereby the screw 78 moves back from the transverse pin 79 and releases the vertical spindle 54 carrying the cross-head. On the other hand, if the lamp holder is empty, the stud 81 rides slightly higher and fails to engage the large roller 76 so that the lever 73 does not pivot and the spindle and cross-head cannot move up.

The large roller 82 seen in Fig. 3 is adapted to engage the transverse bracket 26 and to force it down, whereby to lower the spindle 23 and release the pressure on the lamp 1. The purpose of releasing the pressure on the lamp is in order that the jaws may spin the lamp during the printing operation without being required to exert an excessive force on the lamp base. The lamp may be held in place meanwhile by a suitably directed air jet, not shown in the drawing. The lowering of the spindle caused by the roller 82 permits the stud 81 to engage the smaller roller 77 when the base holder has advanced to the printing station.

This causes the lever 73 to pivot and release the spindle 54 and cross-head 53, thereby allowing the jaws to close for the printing operation.

Timing diagram

The sequence of operation of the different parts of the printing mechanism may be understood most readily by referring to Fig. 8 containing the timing diagram. The printing mechanism angle refers to the angular position of the shaft 33 supporting the cam disc. The zero angle corresponds to the state of the printing mechanism as illustrated in Fig. 3, in connection with which the corresponding position of the jaws may be seen most clearly in Fig. 1a. The indexing of the lamp holders carried on the turret of the finishing machine begins at the 325° angle of the printing mechanism on the preceding cycle, and ends at the 85° angle of the current cycle.

During the interval from 20° to 120° the right-hand slide 10 carrying the printing stamp advances the full extent of its movement, which, in the case of an actual construction, was 2 1/8". Beginning at the 70° angle, the left-hand slide rod 11 moves forward and will have advance 1 1/8" at the 120° angle. The position of the slide rods then is as illustrated in Fig. 1b. It will be observed that the right-hand slide rod has its gripping jaw 7 advanced further than the jaw 8 of the left-hand slide rod. This is to permit the jaws to move in opposite directions during the next portion of the cycle in order to spin the lamp without moving it out of its holder.

During the interval from 0° to 20°, provided a lamp is present in the holder to operate the interlock by deflecting the larger control roller 76, the slide rods rotate in order to allow the stamp to pick up ink from the platen 61. If the base holder is empty, the large control roller is not deflected and the interlock mechanism prevents the jaws from operating and the stamp from picking up ink. At the 85° position, the small control roller 77 is deflected by the projecting stud on the lamp spindle and the interlock mechanism is released whether or not a lamp is present in the holder.

During the interval from 120° to 130° the slide rods are stationary as far as longitudinal movement is concerned, but rotate inwards thereby bringing the jaws together to grip the lamp as indicated in Fig. 1b. During the interval from 130° to 250°, the right-hand slide rod 10 moves back whereas the left-hand slide rod 11 moves forward an equal extent and at the same rate. During this interval, the jaws remain closed and grip the lamp base. It will be recalled that the base is held relatively loosely in its holder at this time by reason of the fact that the lamp holder spindle has been pushed down by the roller 82. The rolling of the base against the jaw 7 causes the characters of the stamp to be imprinted on its peripheral surface.

During the interval from 250° to 260°, the slide rods rotate longitudinally so as to open the jaws and the printed lamp is released in the lamp holder. From the 270° to the 360° positions, both the right-and left-hand slides retreat and return to the rest position corresponding to the 0° angle.

Although the base printing machine illustrated in the drawings has been described in detail as to its component parts, it will be understood that such detail is for the purpose of explanation and not in order to restrict the invention thereto. It is possible to make many variations as to the details of the mechanism in order to adapt it to op-

erate in conjunction with different lamp-making machinery. Moreover, the mechanism can be enlarged or modified to print characters on different sizes and types of lamps or other similar cylindrical devices. The appended claims are therefore intended to cover any such modifications coming within the true spirit and scope of the invention.

What I claim as new and desire to secure by Letters Patent of the United States is:

1. A mechanism for marking characters on the cylindrical portions of devices periodically presented at a work station, comprising a pair of slide rods in substantially parallel alignment, means mounting said slide rods for movement forward toward said device at said station, a pair of gripping jaws mounted in radially displaced alignment at the forward ends of said slide rods, a marking stamp carried on one of said slide rods proximate to one of said jaws, means for rotating said slide rods about their longitudinal axes in order to force said jaws together and grip said device, and means for moving one of said slide rods with respect to the other in order to spin said device between said jaws, thereby to cause the periphery of said device to roll against said stamp.

2. A mechanism for marking characters on the periphery of the cylindrical portions of devices periodically presented at a work station, comprising a pair of slide rods in substantially parallel alignment, means mounting said slide rods for movement forward towards said device at said station, a pair of gripping jaws mounted in radially displaced alignment at the forward ends of said slide rods, a marking stamp carried on one of said slide rods proximate to one of said jaws, means for rotating said slide rods about their longitudinal axes in order to force said jaws together and grip said device, and means for advancing one of said slide rods and simultaneously withdrawing the other in order to spin said device between said jaws while fixed in position at said station, thereby to cause the periphery of said device to roll against said stamp.

3. A mechanism for marking characters on the periphery of the cylindrical portions of devices periodically presented in fixed alignment at a work station, comprising a pair of slide rods mounted in substantially parallel alignment and adapted to move forward towards said device at said station, a pair of gripping jaws mounted on radial fingers at the forward ends of said slide rods and in parallel facing alignment one with respect to the other, a marking stamp carried on one of said slide rods proximate to one of said jaws, means for moving said slide rods forward in order to cause said jaws to encompass said device, a linkage actuated by said means for rotating said slide rods about their longitudinal axes in order to force said jaws together and grip said device, said means being further adapted to advance one of said slide rods and simultaneously withdraw the other in order to spin said device between said jaws while fixed in position at said station, thereby to cause the periphery of said device to roll against said stamp.

4. A mechanism for printing characters on the periphery of the cylindrical bases of electric lamps periodically presented in fixed alignment at a work station, comprising a pair of slide rods mounted in parallel alignment and adapted to slide forward towards said lamp at said station, a pair of gripping jaws held by radial fingers se-

cured to said slide rods at their forward ends, said gripping jaws being straight and extended in substantial parallelism to said slide rods, means for causing said slide rods to advance towards said lamp and said jaws to encompass it on opposite sides, means for rotating said slide rods about their longitudinal axes in order to force said jaws together whereby to grip said lamp therebetween, a printing stamp carried at the forward end of one of said rods in substantial parallel alignment to the gripping jaw associated therewith, said first named means being further adapted to cause one of said rods to slide with respect to the other while said jaws are closed, thereby to roll said lamp against said stamp and imprint the characters of said stamp on the peripheral surface of said base.

5. A mechanism for printing characters on the periphery of the cylindrical bases of electric lamps periodically presented in fixed alignment at a work station, comprising a pair of slide rods mounted in parallel alignment and adapted to slide forward towards said lamp at said station, a pair of gripping jaws held by radial fingers secured to said slide rods at their forward ends, said gripping jaws being straight and extended in substantial parallelism to said slide rods while facing each other, means for causing said slide rods to advance towards said lamp and said jaws to encompass it on opposite sides, means for rotating said slide rods about their longitudinal axes while so advanced in order to force said jaws together whereby to grip said lamp therebetween, a printing stamp carried at the forward end of one of said rods in substantial parallel alignment to the gripping jaw associated therewith, said first named means being further adapted to advance one of said slide rods and simultaneously withdraw the other at the same rate in order to cause said lamp to spin between said jaws while closed and without moving said lamp out of its station, thereby to imprint the characters of said stamp on the peripheral surface of said base.

6. A mechanism for printing characters on the periphery of the cylindrical bases of electric lamps periodically presented at a work station, comprising a pair of rods supported in substantially parallel alignment in guide bearings and adapted to slide along and rotate about their longitudinal axes with respect to said bearings, gripping jaws mounted on radial fingers fastened to said rods at their forward ends and extending in facing alignment parallel to the axes of said slide rods, a printing stamp carried on one of said slide rods in proximity to its associated gripping jaw, cam actuated linkages for causing said slide rods to move forward and rotate whereby to cause said gripping jaws to encompass said lamp and grip it on opposite sides, said linkages being further adapted to advance one of said slide rods while withdrawing the other whereby to spin said lamp between said jaws without moving it out of said work station, said spinning being adapted to roll the base of said lamp against said stamp for printing characters thereon.

7. A mechanism for printing characters on the periphery of the cylindrical bases of electric lamps periodically presented at a work station, comprising a pair of rods supported in substantially parallel alignment in guide bearings and adapted to slide along and rotate about their longitudinal axes with respect to said bearings, gripping jaws mounted on radial fingers fastened to said rods at their forward ends and extending in mutually facing alignment parallel to the

axes of said slide rods, a printing stamp carried on one of said slide rods in proximity to its associated gripping jaw, cam actuated linkages for causing said slide rods to move forward and rotate whereby to cause said gripping jaws to encompass said lamp and grip it on opposite sides, said linkages being further adapted to advance one of said slide rods while withdrawing the other whereby to spin said lamp between said jaws without moving it out of said work station, said spinning being adapted to roll the base of said lamp against said stamp for printing characters thereon, and means for automatically inking said stamp in between printing operations, said means comprising an inking platen located for contacting said stamp during an intermediate rotation of said slide rods.

8. An electric lamp base printing mechanism adapted to operate upon a lamp at a station of a lamp-making machine of the indexing turret type comprising a pair of slide rods mounted in substantially parallel alignment and adapted to move forward towards a station of said machine, a pair of gripping jaws mounted in facing relationship on said slide rods and supported at a substantial radial distance from their axes, a printing stamp carried on one of said rods close to one of said jaws, cam actuated lever linkages for advancing said rods towards said station in order to cause said jaws to encompass said lamp, a cam actuated slide and roller mechanism for rotating said rods about their longitudinal axes in a manner to force said jaws together whereby to grip said lamp therebetween, said lever linkages being further adapted to advance one of said rods with respect to the other in a subsequent operation whereby to spin said lamp between said jaws in order to roll it against said stamp and imprint the characters of said stamp on its base.

9. An electric lamp base printing mechanism adapted to operate upon a lamp at a station of a lamp making machine of the indexing turret type comprising a pair of slide rods supported by guide bearings in substantially parallel alignment and adapted to move forward towards a station of said machine, a pair of gripping jaws mounted in facing relationship on said slide rods and supported at a substantial radial distance from their axes, a printing stamp carried on one of said rods close to one of said jaws and extending parallel to it, a cam actuated lever linkage for advancing said rods towards said station in order to cause said jaws to encompass said lamp,

a cam actuated slide and roller mechanism for rotating said rods about their longitudinal axes in a manner to force said jaws together whereby to grip said lamp therebetween, said lever linkages being further adapted to advance one of said rods and withdraw the other at an equal rate in a subsequent operation whereby to spin said lamp between said jaws in order to roll it against said stamp and imprint the characters of said stamp on its base.

10. An electric lamp base printing mechanism adapted to operate upon a lamp at a station of a lamp making machine of the indexing turret type comprising a pair of slide rods supported by guide bearings in substantially parallel alignment and adapted to slide along and rotate about their longitudinal axes with respect to said bearings, a pair of gripping jaws mounted on radial fingers fastened to said rods at their forward ends and extending in mutually facing alignment parallel to said axes, a printing stamp carried on one of said rods is proximity to its associated gripping jaw and extending parallel to it, a cam actuated lever linkage for advancing said rods towards said station in order to cause said jaws to encompass said lamp, a cam actuated slide and roller mechanism for rotating said rods about their longitudinal axes in a manner to force said jaws together whereby to grip said lamp therebetween, said lever linkages being further adapted to advance one of said rods and withdraw the other at an equal rate in a subsequent operation whereby to spin said lamp between said jaws in order to roll it against said stamp and imprint the characters of said stamp on its base, and means for automatically inking said stamp comprising an inking platen located for contacting said stamp during an intermediate operation of said slide and roller mechanism adapted to pivot said stamp against said platen.

40 LESLIE P. TYLER.
